UNITED STATES PATENT OFFICE.

CHESTER N. STEVENS, OF KENILWORTH, ILLINOIS.

STREET CONSTRUCTION.

1,116,857.

Specification of Letters Patent. Patented Nov. 10, 1914.

Application filed April 13, 1914. Serial No. 831,528.

To all whom it may concern:

Be it known that I, CHESTER N. STEVENS, a citizen of the United States, and a resident of the town of Kenilworth, in the county of Cook and State of Illinois, have invented certain new and useful Improvements in Street Construction; and I do hereby declare that the following description of my said invention, taken in connection with the accompanying sheet of drawings, forms a full, clear, and exact specification, which will enable others skilled in the art to which it pertains to make and use the same.

15 My present invention relates to improvements in a street construction, and it consists, essentially, in the novel and peculiar combination of parts and methods of construction, as hereinafter first fully set forth and described and then pointed out in the claim.

In the drawing already mentioned which serves to illustrate my invention more fully, Figure 1 is a transverse vertical section of a street or thoroughfare embodying my invention. Fig. 2 is a side elevation of a fragment thereof, and Fig. 3 a plan of a street intersection wherein my said invention is employed.

30 Like parts are designated by corresponding characters or symbols of reference in all the figures of the drawing.

The essence of my invention resides in the provision of means to reduce the great loss of life in large cities caused through collisions between automobiles and other vehicles and pedestrians. I have observed that the majority of these accidents are due to pedestrians crossing streets "between blocks", as it were, where, when the traffic is heavy, neither the pedestrian nor the automobile nor driver can keep a sufficiently close watch on each other to insure safety in crossing. Other places at which a large number of accidents occur is in front of the entrances of large office buildings, school buildings, manufacturing establishments, and department stores, where pedestrians are constantly crossing from one side of the street to the other. Accidents at street intersections are comparatively few because at such points, in congested sections, police officers are stationed to direct the flow of foot and vehicle traffic.

55 Automobiles often become unmanageable

and crash into street curbings, over side walks, and into show windows, almost always resulting in injury to one or more persons. Horses become beyond control, with the same result. It is therefore, another aim of my invention to establish means preventing the encroachment upon side walks by horses or motor propelled vehicles as indicated above.

Still another aim of my invention is to provide a construction which will lend itself harmoniously to the "city beautiful" plans now being advocated in many municipalities.

I accomplish the desired results as disclosed in the drawing, in which—

A indicates a street or thoroughfare and A' an intersecting or cross street.

B and B' denote the sidewalks and C and C' the building lines on either side of said lanes of traffic.

D indicates the street surfacing and D' the concrete or other base thereunder.

The curbing on both sides of the street is represented at E, and consists of a foot- 80 ing F embedded in the street base and an upright wall G and G' extending upwardly to a height approximating that of the knees of a man of average height. Along the upper edge of this wall is produced an 85 integral cap H and H'. Said cap, wall and footing are of concrete, cast *en bloc* in sections of suitable length as indicated in O, Fig. 2, and are set in place in the same manner as the present day curbing is placed in 90 position. Suitable reinforcing rods P and P' are secured in the concrete section O to stiffen the cap, wall and footing thereof in an obvious manner.

Formed in and depressed below the surface of the sidewalks B and B' adjacent the walls G and G' are gutters R and R'; and produced in said walls and communicating with said gutters are through openings or scuppers S and S'. The object of these 95 gutters and scuppers is to permit the outflow of surface water on the sidewalks into the street gutters formed by the curbing E.

The curbing, wall, and cap sections extend the entire length of a block, save for a 105 short distance at each intersecting street as seen at T Fig. 3, and form a bulwark against encroachment upon the side walk by unmanageable motor vehicles or runaway horses. While pedestrians wishing to cross a street 110

may, of course, step over the bulwark, yet the presence thereof is a constant reminder of the dangers of crossing at that point.

Lamp posts 10 may be placed at suitable distances apart upon the cap H of the wall G or G' and the whole construction will lend itself harmoniously to the "city beautiful" plans being advocated throughout the country.

10 In front of entrances to large buildings, stores, and the like blocks Z shown in dotted lines in Fig. 1, may be placed adjacent the walls G, G' whereby passengers in automobiles, drawn up alongside said walls, may 15 step from said vehicles to the top of said walls and on to said blocks Z to the sidewalk.

It is to be understood that the curb, wall, and cap sections may be made at a point remote from the place of installation, or suitable forms may be set up when a street pavement is laid down and the curbs and walls produced in place in an obvious manner.

20 Another distinct advantage of my invention is that the employment thereof would eliminate the splash of mud and water due

to the passage of street sprinklers which now spray a portion of the sidewalks in passing, to the great detriment of the clothing of nearby pedestrians. The splashing of mud from passing automobiles will also be prevented.

Having thus fully described my invention, I claim as new and desire to secure to myself by Letters Patent of the United States:

In combination, a street surface and base, curbing having a footing embedded in said base, sidewalks adjacent said curbing, and side walls, integrally formed with said curbing, extending above the surface of said side walks, and forming bulwarks at the outer edges thereof, there being longitudinal gutters in said side walks adjacent said side walls and openings through said walls communicating with said gutters.

25 In testimony whereof, I have hereunto set my hand in the presence of two subscribing witnesses.

CHESTER N. STEVENS.

In the presence of—

W. HARDING,

C. S. STARK.
